UNITED STATES PATENT OFFICE.

ALBERT BESS, OF HAMILTON, OHIO.

MANGLE.

No. 844,773.

Specification of Letters Patent.

Patented Feb. 19, 1907.

Application filed January 21, 1905. Serial No. 242,056.

To all whom it may concern:

Be it known that I, ALBERT BESS, a citizen of the United States, residing at Hamilton, Ohio, have invented a new and useful Improvement in Mangles, of which the following is a specification.

My invention relates to mangles of the class wherein the linen is held in contact with a cylindrical drier by means of an endless apron; and the objects of my improvement are to provide means to simultaneously move and maintain the pressure-rolls a short distance from the drier to prevent them from crushing the buttons on the garments or to cause the rolls to simultaneously exert more or less yielding pressure toward the drier as desired.

These objects are attained in the following described manner, as illustrated in the accompanying drawings, in which—

Figure 1 is an end elevation, with parts broken away, of a mangle embodying my improvement; Fig. 2, a front elevation with parts broken away; Fig. 3, a longitudinal section of one end of the drier and contiguous parts on the line *a a* of Fig. 1; Fig. 4, an inside elevation of the opposite end frame with certain parts connected thereto, and Fig. 5 a sectional view of the turnbuckle on a connecting-rod.

In the drawings the hollow cylindrical drier 7 is formed with end journals 8, whereby it is mounted to rotate in bearings 9, formed in supporting-frames 11. Gear 12, keyed on one of journals 8, engages with driven pinion 13. Endless apron 14 travels in the direction of the arrows in contact with the face of the drier under the usual padded pressure-rolls 15, 16, 17, and 18, over guide-rolls 21, 22, and 23, and tightening-roll 24. Pressure-rolls 15 and 16 are each provided with a pinion 25, engaging with gear 12. The pressure-rolls are each movably hinged on the supporting-frames by means of short arms 26 and are simultaneously adjustable toward or from the face of the drier by means of connecting-rods 27, engaging with flanges 28 and tangent thereto. Said rods are adjustable in length by means of turnbuckles 29, and said flanges are rotatively adjustable on collars 30, which are secured on the respective supporting-frames concentric with journals 8. Horizontal arms 31 project in a forward direction from the flanges, and weights 32, adjustable thereon, cause the pressure-rolls to simultaneously exert a yield-

ing pressure on the apron toward the face of the drier. The pressure-rolls are movable only simultaneously, and any thick material carried by the apron under one of said rolls 60 receives the concentrated pressure of all of them. Rod 33, provided with cams 34 under the respective arms 31, is journaled at its ends in the respective supporting-frames. It is actuated by means of hand-lever 35 65 thereon to cause the cams to move and maintain the arms in an elevated position with the pressure-rolls a short distance from the drier. In this position garments with buttons attached may be passed between the 70 apron and the drier without danger of the buttons being crushed by the pressure-rolls. Guide-roll 38 serves to properly direct the travel of the apron in the usual manner.

Having fully described my improvement, 75 what I claim as my invention, and desire to secure by Letters Patent of the United States, is—

1. The combination of a hollow cylindrical drier, rotatively mounted on supporting-frames, a series of rotative pressure-rolls 80 movably supported on said frames and adjacent to the face of the drier, members attached to the frames concentric with the axis of the drier adjustable means unyieldingly connecting the pressure-rolls thereto, and weights arranged to rotatively move said members and to yieldingly maintain the pressure-rolls collectively in the same relative position toward the drier. 90

2. The combination of a hollow cylindrical drier rotatively mounted on supporting-frames, members attached to said frames concentric with the axis of the drier and rotatively adjustable thereon by means of 95 weights, and pivoted cams, a series of pressure-rolls, movably secured to the frames and adjacent to the face of the drier, and adjustable means unyieldingly connecting said members thereto, whereby the rolls are movable only with said members and simultaneously in relation to the drier. 100

3. In a mangle, the combination of supporting-frames, a hollow cylindrical drier journaled thereon, a plural number of pressure-rolls mounted on the frames and movable toward the face of the drier, an endless apron passing under the rolls and partially around the drier, rotative flanges mounted on the respective frames concentric with 105 the drier and each provided with an arm, weights movable on the respective arms and 110

- adapted to turn the flanges, and adjustable rods pivotally secured at one end to the periphery of the flanges and tangent thereto said rods being connected at the other end 5 with the respective pressure-rolls, whereby said rolls may be simultaneously moved and caused to maintain the apron in contact with the drier under a yielding pressure by means of the weights.
- 10 4. The combination of supporting-frames, a hollow cylindrical drier journaled thereon, a series of pressure-rolls movably secured on the frame and adjacent the face of the drier, flanges movably supported on the respective 15 frames concentric with the axis of the drier, adjustable rods unyieldingly connecting the rolls thereto, and weights adapted to simultaneously move and yieldingly maintain the flanges with the rolls under a yielding pressure 20 toward the drier.
5. In a mangle, the combination of supporting-frames, a hollow cylindrical drier journaled thereon, a plural number of pressure-rolls journaled in swinging bearings secured 25 to the frames, members rotatively ad-

justable on the respective frames, adjustable means unyieldingly connecting the rolls thereto, adjustable weights adapted to actuate said members to simultaneously move and maintain the rolls under a yielding pressure 30 toward the drier, and means adapted to counteract the weights and move the rolls simultaneously in the opposite direction.

6. In a mangle, the combination of end supporting-frames, a hollow cylindrical drier 35 journaled to rotate therein, arms hinged on the frames and provided with bearings, pressure-rolls journaled in the bearings, flanges movably supported on the supporting-frames concentric with the drier, and each 40 provided with an arm, weights movable on the arms, and adjustable connecting-rods attached to the flanges and the respective bearings, whereby the pressure-rolls are movable only simultaneously.

ALBERT BESS.
